(57) **CLAIM**

The ornamental design for a table, as shown and described.

DESCRIPTION

FIG. 1 is a perspective view of a table, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof with a drawer thereof pulled partially out;

FIG. 9 is a perspective view thereof with all drawers thereof pulled partially out;

FIG. 10 is an exploded view thereof, with the tabletop insert inverted to show its bottom;

FIG. 11 is a top view of the tabletop insert portion thereof with the rest of the table removed for ease of illustration;

FIG. 12 is a bottom view thereof;

FIG. 13 is a front elevational view thereof, the rear elevational view being a mirror image thereof; and,

FIG. 14 is a right side view thereof, the left side view being a mirror image thereof.

In the drawings, the broken lines showing screws form no part of the claimed design.

In the drawings, the broken lines on the tabletop and interior of the drawers depict boundaries of the claimed design, and form no part thereof.
